R. T. BREWSTER

FLACON

Filed March 18, 1927

INVENTOR.

Ruby T. Brewster
BY Henry, Barber & McKee

ATTORNEYS.

UNITED STATES PATENT OFFICE.

RUBY T. BREWSTER, OF NEW YORK, N. Y.

DESIGN FOR A FLACON.

Application filed March 18, 1927. Serial No. 21,186. Term of patent 3½ years.

To all whom it may concern:

Be it known that I, RUBY T. BREWSTER, a citizen of the United States, residing at New York city, in the county and State of New York, have invented a new, original, and ornamental Design for a Flacon, of which the following is a specification, reference being had to the accompanying drawing, forming part thereof.

The figure is a perspective view of a flacon, showing my new design.

I claim:

The ornamental design for a flacon, as shown.

RUBY T. BREWSTER.
